UNITED STATES PATENT OFFICE.

CHARLES F. PEASE, OF COLUMBUS, OHIO.

PROCESS FOR FINISHING PHOTOGRAPHICALLY-PRINTED SHEETS.

No. 831,520.

Specification of Letters Patent.

Patented Sept. 18, 1906.

Application filed April 1, 1905. Serial No. 253,224.

To all whom it may concern:

Be it known that I, CHARLES F. PEASE, a citizen of the United States, residing at Columbus, in the county of Franklin and State of Ohio, have invented certain new and useful Improvements in Processes for Finishing Photographically-Printed Sheets, of which the following is a specification.

My invention relates to a process for finishing photographically-printed sheets.

The invention has for its more essential object a process for washing, wringing, or wiping and drying continuous sheets of blueprint paper by a continuous operation.

My purpose is to use the process in connection with what is known as a "continuously-printing" machine, although this is not essential.

Finally the invention contemplates a process which will be simple and inexpensive to conduct and one which will not require the use of expensive or complicated machinery.

In order that my process may be clearly understood, I have devised an apparatus by which the process may be carried out which I have illustrated in the accompanying drawings, wherein—

Figure 1 is a diagrammatical end elevation of the apparatus. Fig. 2 is a front elevation; and Fig. 3 is a partial end elevation of the upper portion of the apparatus, showing a wiping device applied in lieu of the uppermost roller.

I wish it to be understood that I have merely shown the apparatus illustrated in the drawings as one form of the many apparatuses and machines which might be employed.

In carrying out my process in connection with the apparatus illustrated the numeral 1 designates a roll of continuous photographic paper which has been properly printed and is ready to be finished, or in lieu of this roll the paper may be taken directly from the printing-machine. The sheet of paper 2 is led over a plurality of transverse rods 3, arranged in a curve over a trough 4, adapted to receive the washing-water, and arranged so as to maintain the level of the water in the trough at such a height that the sheet 2 will not at any time come in contact with the water, thus keeping the back or rear side of the sheet dry. A guide-rod 5 is arranged over the rods 3, and the paper passes between the said rods 3 and 5. After passing over the rods 3 the paper is led upwardly over trans-

verse rods 6, arranged on an incline, at the back of which is arranged a guard-plate 7, which is formed by continuing the bottom wall of the trough 4 upwardly. The angle of 60 inclination of the rods 6 and the guard-plates 7 is quite steep, so as to allow the falling water a quick descent, and thus prevent the same from saturating the sheet of paper, but acting merely to wash the same as the paper 65 is carried upward. A suitable water-spraying device 8 is located above the rods 6 and intermediately of two transverse rollers 9, between which the paper is passed. The paper is passed over the front of the lower roller 9 and in back of the upper roller and the spraying device arranged so that the water will be sprayed directly on the sheet of paper, and thus running or falling over the outer surface of the same downwardly until it flows 70 off each side of the sheet into the trough 4. The paper after being led back of the upper roller 9 is passed between two suitably-supported wringing-rolls 10, which wring or squeeze the water from the paper, so as to reduce the paper from a wet to a moist condition. It is to be understood that in lieu of one of the rollers 10 a suitable wiping device 75 may be employed. In Fig. 3 I have shown a flat rubber strip 10^a, supported in a grooved bar 10^b, so as to bear on the wet surface of the paper and wipe the superfluous water and moisture therefrom. The sheet of paper after being passed between the rollers 10 or between the roller 10 and the wiping-strip 10^a is 80 led horizontally across and about a roller 11, with which it is held in contact by an endless tape 12, passing over an upper roller 13 and about oppositely-disposed rollers 14. The paper is thus carried around by the tape on 85 its outer surface downwardly across and upwardly to a delivering-roller 15, mounted opposite the roller 11. Both the rollers 11 and 15 are set slightly inwardly, so as to firmly engage with the tape 12, and thus keep the sheet 90 of paper taut. Adjacent the front, vertical run of the tape I arrange any heating device, such as a plurality of steam or hot-water pipes 16, and in some cases it might be found convenient to arrange pipes 17 horizontally 95 below the bottom run of the tape. It will be apparent that after the paper has been once led through the apparatus power suitably applied to the rolls will impart motion to the same and cause the paper to be carried 100 through the apparatus and washed, wrung, and dried, it being understood that while the 105

sheet of paper is passing around the tape 12 the heat generated either by the pipes 16 or 17 will be sufficient to thoroughly dry the sheet.

5 While I have shown and described the above-mentioned apparatus, I wish it understood that the said apparatus forms no special part of this invention; but the essential feature is the process of finishing photographically-printed paper by first carrying the paper upward against falling water to wash the same, then wringing or wiping the paper, and finally drying the same, all by a continuous operation. Photographically-printed paper may in this way be expeditiously and readily finished without the usual handling and laborious methods now commonly employed.

Having now fully described my invention, 20 what I claim, and desire to secure by Letters Patent, is—

1. A process of finishing photographically-printed paper by a continuous operation which consists in first moving the said paper 25 in a dry condition upwardly and simultaneously wetting the printed surface thereof and then drying the paper by artificial means.

2. The process of finishing sheets of photographically-printed paper by a continuous operation which consists in first moving the said sheets in a dry condition upwardly and simultaneously exposing the printed surface thereof to falling water and then drying the 35 same by artificial means.

3. The process of finishing sheets of photographically-printed paper by a continuous operation which consists in first moving the dry sheets upwardly and simultaneously exposing the printed surface thereof to falling 40 water, then removing the superfluous water from the sheets and finally drying the said sheets by artificial means.

4. The process of finishing sheets of photographically-printed paper by a continuous 45 operation which consists in first moving the dry sheets upwardly and exposing only the printed surface thereof to falling water, then removing the superfluous water from the sheets and finally drying said sheets by artificial means.

5. The process of finishing dry sheets of photographically-printed paper by a continuous operation which consists in wetting only the printed surface of the same and drying 55 the sheets by artificial means.

6. The process of finishing dry sheets of photographically-printed paper by a continuous operation which consists in wetting only the printed surface of the same, then removing superfluous water from the sheets and finally drying the said sheets by artificial means.

In testimony whereof I affix my signature in presence of two witnesses.

CHARLES F. PEASE.
